UNITED STATES PATENT OFFICE.

FREDERIC C. MANN, OF EAST BRIDGEWATER, MASSACHUSETTS.

BAT-GATHERING ATTACHMENT FOR COTTON-CONDENSERS.

SPECIFICATION forming part of Letters Patent No. 271,488, dated January 30, 1883.

Application filed October 19, 1882. (No model.)

To all whom it may concern:

Be it known that I, FREDERIC C. MANN, of East Bridgewater, in the county of Plymouth and State of Massachusetts, have invented certain Improvements in Bat-Gathering Attachments for Cotton-Condensers, of which the following is a specification.

This invention relates to cotton-seed linters, gin-cleaners, or other machines in which cotton fibers are compacted and delivered in the form of a bat.

The object of the invention is to provide an attachment for machines of this class adapted to wind the bat of cotton into convenient form as it passes from the machine.

To this end my invention consists in the improved attachment which I will now proceed to describe.

Of the accompanying drawings, forming a part of this specification, Figure 1 represents a side elevation of a portion of the condensing mechanism of a cotton-seed linter provided with my improvement. Fig. 2 represents a top view of the same. Fig. 3 represents a section on line *xx*, Fig. 1.

The same letters of reference indicate the same parts in all the figures.

In the drawings, A represents the perforated or wire-cloth cylinder of a cotton-condenser. B represents a pressure-roll which presses the bat of cotton against the surface of the cylinder, said parts being journaled in a suitable frame and forming no part of my invention. The cylinder A is positively rotated in the direction indicated by the arrow, and with the roll B is covered, as usual, by a bonnet or casing. (Not shown in the drawings.)

In carrying out my invention I provide a loose roll, C, adapted to bear with a yielding pressure on the cylinder A at a point in the rear of the roll B, and also adapted to be rotated by the cylinder, so as to wind upon itself the bat of cotton passing over the cylinder, and to yield or be displaced outwardly as the bat accumulates upon it. I journal the roll C in slots I in the ends of two arms, D D, which are pivoted at E E to ears formed on clamps F F, detachably secured by set-screws G G to the frame of the machine. Said arms are adapted to rise and fall, and therefore permit

the necessary displacement of the roll C. To the under sides of the arms D are attached springs or yielding buffers J, which bear on the frame of the machine, as shown in Fig. 1, and prevent the arms from dropping below the position they occupy when the roll C is in place and bearing on the cylinder A. The roll C is provided with elongated journals C' C', which project far enough outside of the arms D D to serve as handles for the roll as well as journals.

The operation is as follows: The operator rolls the end of the bat of cotton upon the roll C until the bat is sufficiently connected with said roll to be wound thereon by the rotation of the roll which is caused by the cylinder A. As the bat accumulates on the roll the latter is displaced outwardly, the arms D D turning on their pivots. When a sufficient quantity of cotton has been wound upon the roll C the operator severs the bat and removes the roll from the arms D, slips the coiled bat off endwise of the roll, and replaces the roll in the arms D, the latter being supported by the springs J while the roll was removed, so that their slots I are in position to receive the journals of the roll. The rolled piece of bat removed from the roll C can be placed in a receptacle with other similar pieces.

I am aware that a loose accumulating-roll bearing on a large cylinder has been provided in alapping-machine, the journals of said roll being adapted to play in slots formed in fixed standards. It will be seen that by supporting said roll in arms pivoted to the frame of said machine the roll is enabled to move away from the drum with much less resistance and friction than when its journals move in rigid slots.

I claim—

1. In a cotton-condenser, the combination of the supporting-frame, the cylinder A, the arms D D, pivoted to the frame, and the accumulating-roll C, journaled in said arms and adapted to rise and fall therewith, so as to bear with a yielding pressure against the cylinder, as set forth.

2. The improved attachment for a cotton-condenser, composed of two clamps adapted to be detachably secured to the frame of the machine, the arms D D, pivoted to ears on said clamps, and the accumulating roll journaled in

the outer ends of the said arms and adapted to be readily separated therefrom, as set forth.

3. The combination, with the supporting-frame, of the pivoted roller-supporting arms provided with springs or yielding buffers, adapted to bear on said frame and prevent said arms from falling below their proper position when the roll is removed, as set forth.

In testimony whereof I have signed my name to this specification, in the presence of two sub-¹⁰scribing witnesses, this 3d day of October, 1882.

FREDERIC C. MANN.
